UNITED STATES PATENT OFFICE.

ALPHONSO WALRATH, OF FORT PLAIN, NEW YORK.

DESIGN FOR A BROOM-FERRULE.

SPECIFICATION forming part of Design No. 18,110, dated February 21, 1888.

Application filed November 10, 1887. Serial No. 254,860. Term of patent 7 years.

To all whom it may concern:

Be it known that I, ALPHONSO WALRATH, of Fort Plain, Montgomery county, State of New York, have produced a new and useful 5 Design for Broom-Ferrules, of which the following is a specification.

My design relates to the form and ornamentation of broom-ferrules, as shown in the accompanying drawing, forming a part of this 10 specification.

My design consists in the upwardly and inwardly tapering part p' of the ferrule F, where such inwardly-tapering part embraces the handle; a groove, G, arranged in revolution 15 upon the ferrule; a double bead, B B, arranged within said groove, and the lower part, p^2 , of the ferrule where below the recessed groove and double bead arranged to expand downwardly and outwardly.

Having thus described my design, what I 20 claim, and desire to secure by Letters Patent, is—

The design for a broom ferrule, F, consisting of the upper and inwardly tapering top part, p' , the lower downwardly and outwardly 25 tapering part, p^2 , the intermediately-recessed groove G, having the double bead B B arranged therein, as shown and described.

Signed at Fort Plain, New York, this 5th day of November, 1887, in the presence of the 30 two witnesses whose names are hereto written.

ALPHONSO WALRATH.

Witnesses:

JOHN O. WENDELL,
J. E. PICKARD.
